UNITED STATES PATENT OFFICE.

ARCHIBALD L. COURTRIGHT, OF MOUNT HAMILL, IOWA.

HAY-STACKER.

SPECIFICATION forming part of Letters Patent No. 379,102, dated March 6, 1888.

Application filed June 18, 1887. Serial No. 241,780. (No model.)

To all whom it may concern:

Be it known that I, ARCHIBALD L. COURTRIGHT, of Mount Hamill, in the county of Lee and State of Iowa, have invented certain new and useful Improvements in Hay-Stackers and Wagon-Loaders; and I do hereby declare the following to be a full, clear, and exact description of the invention, such as will enable others skilled in the art to which it pertains to make and use it, reference being had to the accompanying drawings, which form part of this specification.

My invention relates to an improvement in hay or straw stackers; and it consists in, first, the combination of the two racks loosely connected together at their inner ends, the two vertical ways or tracks which guide the racks in their vertical movements, adjustable tracks upon which one of the racks moves in dumping its load, elevating ropes and pulleys over which the ropes move, and, second, the combination of two racks, ways for each rack, adjustable tracks, and adjusting supports therefor, all of which will be more fully described hereinafter.

The object of my invention is to provide a machine for stacking hay or straw, which is composed of two racks hinged together, and which have a movement independent of each other, whereby when a pull is exerted upon the elevating ropes the front rack is moved upward at its outer end, so as to prevent any of the hay or straw falling therefrom, and to provide an adjustable track upon which the rear rack travels, so as to enable the load to be dumped.

Figure 1 is a side elevation of a stacker embodying my invention, the elevator being shown raised in dotted lines. Fig. 2 is a plan view. Fig. 3 is a front elevation.

The frame work consists of the three ground-sills A A A, to which is secured near their center the cross-beam B. Secured to opposite sides of the cross-beam B are the vertical timbers C, between the upper ends of which are secured the timbers D, connected together at their upper ends by the cross-beam E.

F are vertical timbers secured to the two outer ground-sills, A, near their rear ends, and connected at their upper ends to the vertical timbers C by the braces G.

Secured to the two outer sills, A, between

the timbers C F, are the timbers, tracks, or ways H, to the upper ends of which are pivoted the hinged tracks I. The outer ends of these hinged tracks I are provided with the bands J, which slide up and down upon the timbers F, and are held in any desired position by any suitable means. By adjusting the bands vertically on the timbers F the tracks are correspondingly raised or lowered at their outer ends, and hence the elevation at which the load is to be dumped can be changed at will. The upper edges of the bands and tracks always form a straight line with each other, as shown, and it is over these two parts which the rollers Z of the rack P must move to a greater or less distance before the load can be dumped. As shown, the bands are so held that their upper edges catch against the outer sides of the uprights F, and are made to bite into the uprights by the weight which is brought to bear upon the tracks. Frictional contact is amply sufficient to hold these bands J in any position into which they may be adjusted; but any suitable means may be used for holding them in position.

K K are braces for preventing any lateral movement of the frame and to give it additional strength.

Fastened to one of the ground-sills A are the two pulleys L, and to the opposite ground-sill is secured the pulley M, around which passes the elevating ropes N.

O represents the front rack, and P the rear one, which are composed of the teeth Q. The front rack, O, is provided with the cross-ties R S, to which the teeth Q are secured. Secured to the cross-tie S near its outer ends are the timbers T, having pulleys U U' journaled in their outer ends, and connected to the cross-beam R by means of the braces V. The two racks P O are hinged together by means of the eyes W and rod X, as here shown, or in any other suitable manner. The cross-ties S Y are provided at their outer ends with the flanged rollers Z for the purpose of reducing friction as the elevators are raised and lowered.

One end of the elevating-rope N passes around one of the pulleys L, then upward over the pulley A', down around the pulley U, which is journaled in the front end of the timber T, then upward, and is secured to the cross-tie E.

The other end of the rope N passes across the frame-work just in the rear of the cross-beam B, around the pulley M, up over the pulley B', down around the pulley U', and has its 5 end secured to the cross-tie E.

The operation of my invention is as follows: The hay or straw is either dumped directly from a wagon upon the rack O or raked thereon in any suitable manner. A pull is then exerted upon the elevating-rope N, which elevates the outer end of the rack O upward until the two racks stand at an angle to each other and form an elevating-frame, in which the hay is securely held. When in this position, the 15 hay slides downward between the two racks, and its pressure upon the two is equal. A continued pull upon the elevating-ropes causes the two racks to travel upward until the rollers Z upon the outer ends of the cross-tie Y 20 reach the top of the timbers H, when they move outward upon the elevating-track I. In this position the rack O continues to move upward, drawing with it the inner end of the rack P, and consequently throwing the outer 25 end of the rack P downward, which forms a continuous incline from the outer end of the rack O to the outer end of the rack P, thus causing the material placed between the two racks to slide from the rack P upon the stack 30 which is being formed. The tracks I, having their outer ends adapted to be moved up and down, it will be readily understood that the rack P can be made to dump its load at any desired height. If desired, the braces or tim-

bers H, to which the adjustable track I is piv- 35 oted, may be made in two parts in order to allow a greater adjustability of the tracks I.

The elevator herein described is also well adapted for loading wagons as well as for 40 stacking hay or straw.

Having thus described my invention, I 40 claim—

1. The combination of the two racks loosely connected together at their inner ends, the two ways or tracks C H, tracks I, the elevating- 45 ropes, and suitable guiding-pulleys, the ways H being shorter than the ways C, so that the rear rack will drop and dump the load, substantially as described.

2. The combination of two racks loosely connected together at their inner ends, ways or 50 tracks for each rack, adjustable tracks I, connected to the rear ways, and adjusting supports therefor, and the elevating-ropes and guiding-pulleys, substantially as set forth.

3. The combination of the two ways or guides C H, the rack O, provided with the timbers T and pulleys U U', the friction-rollers Z, the 55 rack P, loosely connected to the rack O, the adjustable tracks I, loops J, and elevating-ropes and guiding-pulleys, substantially as specified.

In testimony whereof I affix my signature in presence of two witnesses.

A. L. COURTRIGHT.
